TUBE DEBURRING TOOL

Arthur H. Seflin, 6086 Cashio St.,
Los Angeles, Calif. 90035

Filed May 29, 1973, Ser. No. 364,525

Term of patent 14 years

Int. Cl. D8—03

U.S. Cl. D54—4

Fig. 1.

Fig. 2.

Fig. 3.

Fig. 5.

Fig. 4.

FIG. 1 is a perspective view of a tube deburring tool embodying my new design;

FIG. 2 is a side elevational view thereof;

FIG. 3 is an end view thereof looking in the direction of the arrows 3—3 in FIG. 2;

FIG. 4 is an end view thereof looking in the direction of the arrows 4—4 in FIG. 2; and

FIG. 5 is a side elevational view thereof similar to FIG. 2 but with the tool rotated a partial turn.

I claim:

The original design for a tube deburring tool, as shown and described.
